ROLLIN ABELL, OF MILTON, MASSACHUSETTS

ENGINE STARTER

Application filed October 23, 1932. Serial No. 314,505.

This invention relates to starters for internal combustion engines and more especially to starters of the type in which a starting pinion is initially maintained in an inoperative position but automatically shifted into geared relation with the engine by the first stages of rotative motion of the starting motor.

In commercial engine starters of the type above mentioned, the motive power is furnished by electric motors that have exceedingly rapid acceleration, so rapid in fact that the teeth of the starting pinions and the engine gears with which the pinions cooperate are subjected to violent impacts when their end faces butt one against another as the pinion moves axially toward its operative position. When tooth-butting occurs it is commonly followed by clashing of the pinion and the engine gear, in the course of which the pinion takes on the accelerative rotation of the starting motor so quickly that the teeth of the pinion, instead of working into the spaces between the teeth of the engine gear, ride over the ends of the latter teeth and cause mutilation of the teeth. Various devices have been proposed to avoid mutilation of the teeth from this cause but they have not proved to be entirely satisfactory for one reason or another.

Again, even when the pinion of an engine starter goes into mesh with an engine gear without causing any mutilation of the teeth, the train of mechanism is subjected to a sudden and violent strain at the instant of picking up the load and also, in some cases, when back-firing of the engine occurs, unless some yielding or cushioning connection is interposed between the starting motor and the starting pinion. Various devices have heretofore been proposed to relieve this condition but they too have not been entirely satisfactory.

With the foregoing considerations in view, an object of the present invention is to provide an improved engine starter that will not only guard against mutilation of the teeth of the starting pinion and of the engine gear in the event of tooth-butting, but will also insure prompt meshing of the starting pin-

ion and the engine gear following tooth-butting, so that the teeth of the pinion will not overrun the teeth of the engine gear.

Another object of the invention is to provide an improved engine starter that will be relatively quiet in operation, even in the event of momentary arresting of the starting pinion by the teeth of the engine gear when the pinion is moving from its initial position to its operative position.

Still another object of the invention is to provide an improved engine starter that will yield sufficiently, when occasion requires, to relieve the starting motor and its shaft from excessive or injurious stresses at the instant of picking up the load and at times when back-firing of the engine occurs.

To these ends a novel feature of the invention consists in an axially movable assemblage comprising essentially two cooperative friction clutch members of which the driven member is provided with a starting pinion, the formation and arrangement of the parts forming the clutch being such that they are forced with increasing pressure one against the other as the assemblage moves from its initial position to its operative position. As shown, the axially movable assemblage is opposed, in its movement from its initial position to its operative position, by a compression spring arranged to develop increasing driving power of the clutch parts. This spring is preferably under no initial compression, its complete relaxation, when the assemblage is out of gear, being desirable to prolong its resilient life, to facilitate declutching when the assemblage moves out of gear after effecting operation of the engine, and to facilitate the first stages of axial movement of the assemblage when the latter is set in operation to start the engine.

In the illustrated construction the spring above referred to is also utilized to return the axially movable assemblage to its inoperative position or at least to initiate such return movement, at the instant when the engine, starting to operate under its own power, drives the pinion at a rate of speed faster than that of the starting motor. Moreover, provision is made for utilizing the repelling

action of this spring to guard against demeshing of the pinion when, for example, the expansive action of unfired compressed gases in the cylinders of the engine causes pulsating rotation of the engine gear prior to actual operation of the engine under its own power. The illustrated construction comprises a cam of irregular contour for effecting axial movement of the starting pinion from its initial position to its operative position, and also for transmitting the operative rotation from the starting motor to the starting pinion. This cam is provided with two distinct operative faces arranged in stepped relation, the first of which has a sufficient range of action to shift the starting pinion from its inoperative position to its operative position, and the second of which is effective to apply supplemental increments of clutching force to the members of the aforesaid cone clutch and thereby to develop the clutching power in proportion to the resistance of the engine to the starting effort.

Referring to the drawing,

Fig. 1 is a side elevation of an engine starter embodying the several features of the present invention, the parts being shown in their initial or inoperative positions relative to a gear of an internal combustion engine;

Fig. 2 illustrates the starting mechanism in longitudinal section, and in this figure also the parts stand in their initial or inoperative positions;

Fig. 3 is a side elevation of one of the parts comprising the starting pinion and the driven member of the friction clutch;

Fig. 4 is an end elevation of the part shown in Fig. 3;

Fig. 5 is a development of a portion of the cam member which is also the driving member of the friction clutch; and

Fig. 6 is an elevation of a resilient wire ring for locking the set screw by which the operating member of the starting mechanism is secured to the shaft of the starting motor.

The element indicated at 10 in Fig. 1 is a portion of the casing of an electric starting motor, this element furnishing a bearing for a starting shaft 12 such as the armature shaft 50 of the motor. The element indicated at 14 in Figs. 1 and 2 represents a portion of the fly-wheel of an internal combustion engine, and the element indicated at 16 represents a portion of a spur gear carried by the fly-wheel. The starting shaft 12 projects past the engine gear 16 to support the elements of the automatic starting mechanism hereinafter described.

The outboard end of the shaft 12 is provided with a shoulder 18 and with a smooth, cylindric extension 20 of smaller diameter than the main body of the shaft. An operating unit 22 is fixed to the outer end of the extension 20 by a key 24 and a set screw 26, the key being arranged to transmit rotation of

the shaft to the unit 22, and the set screw being arranged to prevent axial movement of the unit 22. For the latter purpose a socket 28 (Fig. 2) is formed in one side of the extension 20 to receive the inner end of the set screw. The unit 22 comprises a hub or sleeve portion and preferably two diametrically opposite lugs or stud portions 30, 30 projecting radially therefrom. The hub portion of the unit 22 is provided with a circumferential groove in register with the set screw 26, the purpose of the groove being to receive a split locking ring 32 (Fig. 6) of resilient wire for holding the set screw against unscrewing. The wire of which the ring 32 is made is of a size to occupy a screw-driver slot formed in the outer end of the set screw.

The lugs or studs 30 formed on the operating unit 22 are preferably cylindric in form. They cooperate with cam surfaces formed on a sleeve 34. This sleeve is one member of an axially movable assemblage that also includes an inner sleeve 36. The sleeve 36 is provided at one end with spur teeth forming a starting pinion 38 and at the other end with a cone-shaped portion 40 that constitutes the driven part of a frictional cone clutch. One end of the sleeve 34 surrounds the cone portion 40 and is provided with an internal cone-shaped surface 42 to provide a friction clutch by which rotation is transmitted from the sleeve 34 to the sleeve 36. The two members of the cone clutch are maintained in the nested relation shown in Fig. 2 by springs hereinafter described.

The driven member 36 of the clutch is bored at its outboard end to receive the extension 20 of the starting shaft and is counterbored to provide a chamber 44. The inboard end of the sleeve 36 is supported by a larger portion of the shaft 12, the parts being fitted to provide for axial movement of this sleeve relatively to the shaft, and also to provide for relative rotation of this sleeve and the shaft.

It is to be observed that the pinion portion of the sleeve 36 always bears on the larger portion of the shaft 12 and is not only centered thereby throughout the axial travel of the sleeve but is braced thereby against trans-axial stresses brought into play by the tendency of the pinion teeth to recede from the engine gear 16 under rotational effort. This utilization of the larger portion of the shaft to sustain the trans-axial stresses is especially desirable to relieve the relatively slender extension 20 from the common causes of bending, of which backfiring is one. The chamber 44 is occupied by a relatively strong compression spring 46 and by a relatively weak compression spring 48, both of which encircle the extension 20. A flanged washer 50 is preferably interposed between the two springs to engage the shoulder 52 of the sleeve 36 and thereby put the heavy spring 46 under compression without subjecting the

light spring 48 to heavy stress. The washer is free to slide axially on the extension 20 and has a free sliding fit in the sleeve 36. The aggregate axial dimension of the two springs and the interposed washer 50 is preferably just equal to the maximum distance between the shoulder 18 of the shaft and the shoulder 52 of the sleeve 36. Thus both springs are fully relaxed when the starting mechanism is in its initial position, but the springs are nevertheless effective to maintain the pinion 38 out of contact with the engine gear 16 and to prevent end-shake of the driving member 34 and the driven member 36 of the clutch.

The member 34 of the axially movable assemblage is provided with duplicate cam surfaces to cooperate respectively with the lugs or studs 30. Each of these cam surfaces, as shown, comprises two inclined steps 54 and 56, the step 54 being effective to shift the pinion 38 from its inoperative position to its operative position in meshed relation with the engine gear 16, and also to apply a considerable rotative effort to the pinion through the members that form the clutch. The step 56 is effective to develop supplemental pressure of the clutch members one against the other after the pinion 38 has been shifted to its operative position. The break or landing 30 between the steps 54 and 56 of the cam includes a convex hump or shoulder 58 and a concave depression 60. The two steps of the cam are inclined in the same general direction but are offset from alignment with each other, the hump 58 and the depression 60 providing a surface of ogee curvature connecting the steps to lead the cooperative stud portion 30 from one step to the other and vice versa.

When the parts occupy their initial positions as shown in Figs. 1 and 2, the stud portions 30 occupy the positions indicated at *a, a* in Fig. 5. The inertia of the transmission couple 34, 36 prevents rotation of these parts during the first stages of rotation of the operating unit 22. Consequently, when the starting motor is set in operation, the first effect of the stud portions is to shift the transmission couple axially as these stud portions progress along the cam surfaces 54. If the teeth of the starting pinion 38 butt the teeth of the engine gear 16 the member 34 takes on rotation of the operating unit and transmits this rotation through the friction clutch 42, 40 to the pinion. At this stage the pressure of the frictional clutching surfaces one against the other is effective to clear the teeth of the pinion from the ends of the teeth of the engine gear, whereupon the pinion teeth find slight entrance between the teeth of the engine gear before the next contact of teeth occurs. Now, the rotation of the pinion is arrested by the engine gear, and the arresting effect is passed along to the driving member 34 by the friction sur-

faces of the clutch, no mutilation of the gear teeth resulting since the clutching pressure at this instant is very light and the clutch members may slip without much driving effort.

During this stage of the operation the internal shoulder 52 of the driven member 36 advances to the washer 50, thereby putting the light spring 48 under compression, but the shoulder does not reach the washer until after the pinion has entered into meshed relation with the engine gear and been arrested thereby.

Now the stud portions 30 continue to advance along the cam surfaces 54, thereby causing the shoulder 52 to engage the washer 50 and thereby put the heavy spring 46 under compression. This stage of compression continues until the stud portions 30 ride over the humps 58 of the cam member, and at that point the clutching effect of the conical portions 42, 40 is nearly, if not quite, sufficient to cause rotation of the engine wheel 14. In any event, the stud portions 30 pass the humps 58 and advance along the secondary cam surfaces 56 until the convolutions of the heavy spring 46 become entirely closed and positively arrest the axial movement of the transmission couple 34, 36. At this point of the operation the positions of the stud portions relative to the cams is that indicated at *b* in Fig. 5.

Now, the driving member 34 of the transmission couple is positively rotated by the stud portions 30 but the driven member 36 is driven solely by the friction of the clutching surfaces 42, 40 so that no sudden shock or impact can ever occur as a result of picking up the load or as a result of back-firing of the engine.

If, for any reason, the load on the starting pinion is in excess of the clutching power of the members 34 and 36, the member 34 will slip relatively to the member 36 even though the cooperative effect of the stud portions 30 and the cam steps 56 tends constantly to wedge the member 34 more tightly against the driven member of the clutch. Again, in the event of reverse rotation of the engine gear 16, in consequence of back-firing, the members of the friction clutch will slip relatively to each other without subjecting any part of the mechanism to injurious strain.

It frequently happens that an internal combustion engine does not start immediately under its own power even though power impulses may occur in one or more of its cylinders. In such a case, the uneven action of the engine causes pulsations in the rotation of the fly-wheel and the gear 16 carried thereby. These pulsations are passed along through the driven member 36 to the driving member 34 of the clutch, with the result that the stud portions 30 run down and up

on the inclined cam steps 56. At the same time the repelling action of the heavy spring 46 tends to return the pinion 38 to its initial position, but to guard against demeshing of the pinion and gear under the conditions just described, the cam member is provided with the humps 58. Under such conditions the stud portions 30 may take positions such as that indicated at *c* in Fig. 5, and may waver between positions *b* and *c*, but so long as the starting effort of the shaft 12 continues the humps 58 are effective to prevent demeshing. The reaction of the heavy spring 46 is instrumental in preventing the stud portions 15 from running back over the humps 58.

On the other hand, as soon as the engine starts to operate normally under its own power, it drives the fly-wheel and the gear 16 at a speed so much greater than the speed of 20 the starting pinion 38 that it causes the humps 58 to overrun the stud portions 30, whereupon the stud portions run down on the steps 54 of the cam member and permit the spring 46 to demesh the pinion and return the parts to 25 their initial positions. The stud portions are thus returned to the positions indicated at *a* in Fig. 5, and the speed of rotation of the cam member 34 is positively checked to a speed exactly equal to that of the stud portions, thus freeing the driven member 40 of 30 the clutch from the driving surface 42. The springs 46 and 48, having been relaxed during the process of demeshing the pinion, leave the clutch members free from clutching pressure, 35 but since they completely fill the axial dimension of the chamber 44 from the shoulder 18 to the shoulder 52, they not only prevent end-shake of the member 36 but also cause the clutch member 40 to support the sleeve 34 in 40 concentric relation to the starting shaft.

The described construction is particularly effective to prevent excessive torsional stresses due to rapidity of acceleration of the starting motor under normal conditions as well as 45 under abnormal conditions, since, in any case, the driving member 34 of the friction clutch may slip relatively to the driven member both during the operation of shifting the pinion axially to its operative position and while the 50 pinion is held in its operative position with the spring 46 fully compressed.

I claim:

1. An engine starter comprising a rotary and axially movable member provided with a 55 starting pinion, a spring arranged to oppose movement of said member axially to its operative position, a rotary and axially movable transmission member arranged to shift said pinion member to its operative position against the stress of said spring, said members being provided with complementary friction surfaces to form a driving clutch, and a rotary operating member arranged to cooperate with said transmission member, one of the two latter said members being pro-

vided with a cam surface with which the other cooperates to shift said pinion member to its operative position and to effect a starting operation through said friction surfaces in consequence of the opposition of said spring. 70

2. An engine starter comprising a rotary and axially movable member provided with a starting pinion, a spring arranged to oppose movement of said member axially to its operative position, a rotary and axially movable transmission member arranged to shift said pinion member to its operative position against the stress of said spring, said members being provided with complementary conical friction surfaces to form a driving clutch, and a rotary operating member arranged to cooperate with said transmission member, one of the two latter said members being provided with two successively operative cam surfaces in stepped relation to shift said pinion member to its operative position by intermittent stages and to develop increased clutching power of said friction surfaces in 80 each of said stages. 85

3. An engine starter comprising a rotary and axially movable member provided with a starting pinion, an initially relaxed spring arranged to repel said member axially from its operative position to an inoperative position, a rotary and axially movable transmission member arranged to shift said pinion member to its operative position and thereby put said spring under stress, said members being provided with complementary friction surfaces forming a driving clutch, and a rotary operating member arranged to cooperate with said transmission member, one of the two latter said members being provided with a two-stroke cam surface with 95 which the other cooperates to shift said pinion member with successive individual steps to its operative position by forcing said friction surfaces one against the other. 100

4. An engine starter comprising a rotary and axially movable member provided with a starting pinion, a relatively weak spring and a relatively strong spring both arranged to oppose axial movement of said pinion member from an inoperative position to its operative position, the weaker one of said springs being effective prior to the stronger one, a rotary and axially movable transmission member arranged to shift said pinion member to its operative position against the resistance of said springs, said members being provided with complementary conical friction surfaces forming a driving clutch, and a rotary operating member arranged to cooperate with said transmission member, one of the two latter said members being provided with a cam surface with which the other cooperates to shift said pinion member to its operative position by forcing said conical friction surfaces one against the other. 110 115 120 125 130

5. An engine starter comprising a rotary and axially movable member provided with a starting pinion, two springs arranged to oppose axial movement of said pinion member from an inoperative position to its operative position, one of said springs being effective prior to the other, a rotary and axially movable transmission member arranged to shift said pinion member to its operative position against the resistance of said springs, said members being provided with complementary conical friction surfaces forming a driving clutch, and a rotary operating member arranged to cooperate with said transmission member, one of the two latter said members being provided with a cam surface with which the other cooperates to shift said pinion member to its operative position by forcing said conical friction surfaces one against the other. 75
- 10 6. The combination with an internal combustion engine provided with a gear by which it may be started, of starting mechanism comprising a rotary and axially movable member provided with a starting pinion, a rotary and axially movable transmission member arranged to shift said pinion member axially from a non-meshing position to a meshing position with respect to said gear, said members having complementary friction clutching surfaces by which such shifting movement is imparted to the pinion member, a spring arranged to oppose such shifting of said pinion member and thereby develop increasing clutching effect of said surfaces, and a rotary operating member arranged to cooperate with said transmission member, one of the two latter said members being provided with a cam surface with which the other cooperates to shift said pinion member to its operative position by forcing said clutching surfaces one against the other. 80
- 15 7. An engine starter comprising a rotary and axially movable member provided with a starting pinion, a rotary and axially movable transmission member arranged to abut said pinion member and move it axially to its operative position, the abutting surfaces of said members being constructed and arranged to form a friction driving clutch, a spring arranged to oppose axial movement of said pinion member to its operative position and thereby develop increasing clutching power of said clutch, and a rotary operating member arranged to cooperate with said transmission member, one of the two latter said members being provided with two successively operative cam steps inclined in the same general direction but offset from alinement with each other the first of which is effective to shift said pinion member to its operative position and to build up the clutching power of said clutch, and the second one of said cam 85
- 20 90
- 25 95
- 30 100
- 35 105
- 40 110
- 45 115
- 50 120
